UNITED STATES PATENT OFFICE

ARCHIBALD B. CALLAWAY, OF READSTOWN, WISCONSIN

ROAD SHOULDER MAINTAINER

Application filed August 13, 1931. Serial No. 556,906.

The present invention relates to a machine for maintaining road shoulders and has for its prime object to provide a machine to remove banks along guard rails or posts along the road which are formed by the wearing away of the rod, particularly gravel, dirt and other similar roads.

Another important object of the invention resides in the provision of an apparatus of this nature in the form of an attachment for a tractor, the apparatus being exceedingly simple in its construction, easy to manipulate and adjust, inexpensive to manufacture, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a top plan view of the apparatus embodying the features of my invention showing the same on the rear end of the tractor.

Figure 2 is a longitudinal sectional view therethrough.

Figure 3 is a vertical transverse section taken substantially on the line 3-3 of Figure 2.

Figure 4 is a detail section taken substantially on the line 4-4 of Figure 2, and

Figure 5 is a detail section taken substantially on the line 5-5 of Figure 1.

Figure 6 is a detail view of one of the chain links.

Referring to the drawings in detail it will be seen that the letter T denotes generally a tractor including a platform 5 having a depending flange 6 at the rear edge thereof.

A pair of spaced angle brackets 7 are mounted on the flange 6 one above the other to receive a pin 8 through openings therein. A pair of upright bars 9 are secured as at 10 to the flange 6 and converge upwardly toward each other and incline upwardly and

rearwardly and have a cross member 11 on the upper end thereof.

Suitable braces 12 are connected to upper intermediate portions of the upright bars 9 and to the platform 5. A cross bar 14 is disposed between intermediate portions of the upright bars 5. A curved elongated guide plate 16 is secured to the center of the cross bar 14 and curved upwardly and rearwardly and is formed with a forward extension at 17 riveted as at 18 to the cross member 11. The cross member 11 on its forward end has a depending flange plate 19 through which is journaled a shaft 20 with the wheel 21 on the rear end thereof and the forward end thereof being threaded. This shaft extends through an opening in the guide plate 16. A U-shaped member 23 straddles the guide 16 and the cross portion thereof has an opening through which the shaft 20 extends. On the ends of the U-shaped member 23 are outwardly directed ears 24 riveted to an angular member 25 through which the threaded portion of the shaft extends and is threaded in a nut 26 fixed to the angle cross member 25. This cross member 25 is formed with slots 27 of a well known type having forward ends larger than the rear ends so that links of chains 28 may be engaged therewith for proper adjustment as will be more clearly apparent as the description proceeds.

A plate 28' is formed with an opening 29 through which the pin 8 extends. The plate is loosely mounted with respect to the pin. Angle bars 30 have forward portions secured together in abutting relation by suitable means 31 and the rear end portions diverge rearwardly from each other as at 32 and are secured to a cross angle iron 33 bolted as at 34 on a mold board 35. These bolts 34 also hold on the mold board a blade 36. The adjacent edges of the blade and the mold board are beveled as indicated to advantage in Figure 5. The end link of each chain 28 is denoted by the numeral 40 and is shown in detail in Figure 5. This link is large at one end and rather narrow at the other end so that instead of the end of the chain dangling, it may be held as shown to advantage in Fig-

ure 2. These chains 28 are secured as at 41 to the mold board 35 and braces 42 extend from the means 42 to the portions 32 of the angle bars 30.

5 By turning the wheel 21 it will be readily appreciated that the mold board may be lifted and lowered as desired. In using this apparatus on the rear of the tractor, the tractor is run back and forth across the road and 10 the shoulders are shaved off as to provide proper drainage for the gravel, dirt, or like road.

15 It is thought that the construction, operation, utility and advantages of this invention will now be quite apparent to those skilled in this art without a more detailed description thereof.

20 The present embodiment of the invention has been described in considerable detail merely for the purposes of exemplification since in actual practice it attains the features of advantage enumerated as desirable in the statement of the invention and the above description.

25 Having thus described my invention, what I claim as new is:

30 In combination, the rear end of a tractor and an apparatus including a pin mounted on the rear end, a plate loosely mounted on the pin, bars secured to the plate and extending rearwardly therefrom in abutment and merging into rear extensions diverging rearwardly from each other, a mold board on the ends of the rear extensions, and means for raising 35 and lowering the mold board comprising uprights from the rear end of the tractor, a shaft, means for rotatably mounting the shaft between the upper ends of the uprights, a member threaded on the shaft, and chains 40 connecting the member with the mold board.

45 In testimony whereof I affix my signature.
ARCHIBALD B. CALLAWAY.
